J. W. SHEPERDSON

ROLLING MILL

Filed May 13, 1926

INVENTOR:
John W. Sheperdson

By Attorney
Geo. P. Kennedy, Jr.

UNITED STATES PATENT OFFICE.

JOHN W. SHEPERDSON, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

ROLLING MILL.

Application filed May 13, 1926. Serial No. 108,937.

The present invention relates to rolling mills. The invention resides in a novel disposition and arrangement of the stands of rolls in a rolling mill, particularly adapting it as a merchant mill, to a wide diversity of products, while at the same time obtaining the maximum of flexibility in the rolling operation and a wide range of selection in the use of the various stands of rolls.

10 The above and other objects are obtained, as hereinafter described, without sacrifice of the tonnage capacity of the mill and with an exceedingly compact arrangement of the mill apparatus, all as fully set forth in the following description, in connection with which reference is had to the accompanying drawing, whose single figure is a diagrammatic plan view of rolling mill apparatus arranged in accordance with the invention.

20 Referring to said drawing, the preliminary reduction of the stock, as received from a heating furnace, not shown, is effected in a roughing mill, here shown as constituted by four stands of rolls 1, 2, 3 and 4. These

25 four roughing stands are driven through the usual gearing from any suitable source of power, as for instance, a motor 13; and the arrangement and spacing of these stands is such that the stock runs free between the

30 rolls 1 and 2 and between the rolls 2 and 3. The rolls 3 and 4 however, are arranged in juxtaposition for continuous operation. The stock, as elongated and reduced in section by this preliminary rolling, is delivered onto a

35 suitable runout 14.

A broadside transfer mechanism 15 of any well known construction is interposed between the runout 14 and a longitudinal conveying mechanism 16, the latter providing 40 conveying rolls, not shown, which run in the opposite direction from the conveying rolls of the runout 14. After the stock from runout 14 has been transferred broadside to the conveying device 16, it is passed through the 45 stands of rolls 5 and 6, the same being arranged in juxtaposition for continuous operation, and driven, through suitable gearing, from the motor 13.

Another runout 17 receives the stock from 50 the rolls 5 and 6, and a second broadside transfer mechanism 18 is interposed between said runout 17 and a longitudinal conveying means 19. The latter delivers the stock to stands of rolls 7 and 8, which are driven

through suitable gearing from motor 13 in 55 the same direction as the stands of rolls 1, 2, 3 and 4 and which are arranged in juxtaposition for continuous operation upon the stock.

A suitable runout 20 receives the stock from the continuously arranged stands of 60 rolls 7 and 8, and if desired, said stock may be delivered by said runout 20 to a cooling bed 21 of any well known construction. If further rolling of the stock is desired, the apparatus provides a third broadside transfer 65 mechanism 22 interposed between the runout 20 and another longitudinal conveying means 23. The latter serves for the delivery of the stock to a single stand of rolls 9, which constitutes part of a finishing mill, here shown 70 as consisting of the four stands of separated rolls 9, 10, 11 and 12, all, as here shown, being driven in alternate directions, through suitable gearing from motor 13.

A Y-transfer conveying mechanism 24, of 75 well-known construction, receives the stock from the rolls 9, and provides the usual means, in the form of skewed conveyor rolls 25, 25 for effecting the travel of each piece as received thereon in the opposite direction, so as to present the rear end of said piece to the next succeeding stands of rolls 10. A similar Y-transfer conveying mechanism 26 is interposed between the stands of rolls 10 and 11 of the finishing mill, and a 80 third Y-transfer conveying mechanism 27 is likewise interposed between the stands of rolls 11 and 12 of said mill. From the rolls 12, a suitable runout 28 is adapted to deliver the stock to a cooling bed 29 of any 85 desired construction.

The arrangement above described possesses a number of advantages over previously employed similar arrangements wherein provision is made in the roughing mill for continuous rolling, and where the rolling is done by a plurality of rolls arranged for operating upon the stock singly in rolls 1 and 2 and in continuous relation in succeeding pairs of rolls. In such previous arrangements, as distinguished from the present arrangement, it has been customary to employ two or more pairs of continuously arranged roll stands in the roughing mill, instead of the single pair 3, 4 herein shown; 95 in such an arrangement, the consequent spacing of these additional continuously arranged stands beyond the rolls 3 and 4, to

enable the bar to run free between the pairs of continuous stands, gives, under the conditions previously used, considerable length to the roughing mill, and thus makes the last stand of roughing rolls and consequently the finishing rolls so far removed from the first stand of rolls in the roughing mill, that an operator experiences great difficulty in covering the distances in a mill so arranged.

Furthermore, in the previously existing rolling mills of this type, a much longer broadside transfer mechanism for the product of the roughing mill than the broadside transfer mechanism 15 herein shown is necessary and this, in turn, necessitates a longer broadside transfer mechanism to receive the stock from the intermediate rolls of the mill, corresponding to the broadside transfer mechanism 18 herein shown. In the present construction, not only are the broadside transfer mechanisms 15 and 18 shorter than the corresponding transfer mechanisms in previous rolling mills of this type, but in addition, the usual connecting table between the pairs of continuously arranged stands of rolls in the roughing mill is dispensed with; consequently, the present arrangement is not only cheaper to build, but being shorter, requires a shorter building to house it.

The present arrangement gives the maximum of flexibility, resulting from interrupted rolling, without sacrifice of tonnage, resulting from continuous rolling. For example, continuous rolling is secured in the pairs of continuously arranged roll stands 3 and 4, 5 and 6, and 7 and 8, whereas in previous mills of this type, only two pairs of continuously arranged stands were provided,—the passes corresponding to 7 and 8 herein, being provided by separated stands of rolls, with an interposed broadside transfer mechanism corresponding to the broadside transfer mechanism 18, but greater in length. In the present arrangement, the disposal of these passes 7 and 8 in continuous relation aids materially in maintaining the temperature of the stock, in that its passage through the two roll stands can be performed in practically the same time that it took to pass through one of these stands in the previous arrangement.

From the standpoint of flexibility, the present arrangement permits a greater latitude in the choice of passes than the previous arrangement above described. For example, with the use of all twelve passes, four free passes 9, 10, 11 and 12 are provided beyond the last continuous rolling operation in the passes 7 and 8, and this is sufficient for the production of accurate sections. Or, if desired, ten passes may be employed by rolling through the stands 5 and 7 and by dummying through the stands 6 and 8.

Nine passes can be used by dummying

through stand 4, in addition to dummying through the stands 6 and 8. Eight passes can be used by employing the stands of rolls 1, 2, 3, 4, 5, 7, 9 and 12, and seven passes can be used by employing this same arrangement with the omission of the stand 4. While the same omissions can be made in the previously used mill above described, it is evident that the stock in passing through said mill must traverse a greater distance than that required to be traversed in the present arrangement. Another alternative offered by the present arrangement is the delivery of the stock from the stand of rolls 8 to the cooling bed 21, this involving the use of the passes 1 to 8 inclusive, or, if desired, a smaller number of passes, by dummying through whatever stands of rolls seems desirable.

As shown in the drawing, a connection 30 may be provided between the Y-transfer conveying mechanisms 24 and 27, so that the stock, if desired, after passage through the rolls 9 may be finished by passage through the rolls 12,—this cutting out the reductions normally effected by passage through the rolls 10 and 11. Furthermore, as shown at 31, a broad side transfer mechanism may be provided between the longitudinal conveyor 16 and the runout 20, thus making it possible, when desired, to transfer the stock broadside from the runout 14 to the longitudinal conveyor 23, without passing it through any of the roll stands 5, 6, 7 and 8.

I claim:

1. In apparatus of the class described, a roughing mill comprising a train of aligned stands of rolls, of which the last pair only are arranged in juxtaposition for continuous operation, in combination with succeeding pairs of continuously arranged stands of rolls, offset laterally at increasing distances from said roughing train, a plurality of single stands of rolls for operation on the stock beyond said pairs of continuously arranged stands, means for effecting successive broadside movements of the stock following its passage through said roughing train and each of said continuously arranged pairs of stands, and a Y-transfer conveying mechanism for delivering the stock from each of said single stands to the next succeeding single stand.

2. In apparatus of the class described, a roughing mill comprising a train of aligned stands of rolls, of which the last pair only are arranged in juxtaposition for continuous operation, in combination with succeeding pairs of continuously arranged stands, offset laterally at increasing distances from said roughing train, means selectively operable to render one or the other stand of any of said pairs of stands inoperative during the passage of the stock therethrough, and means for finishing the rolling of said stock

by passage through one or more of a plurality of single stands of rolls, offset laterally at increasing distances from the last pair of continuously arranged stands of rolls.

3. In apparatus of the class described, a roughing mill comprising four stands of rolls, with the last two stands only arranged in juxtaposition for continuous operation, an intermediate mill comprising a plurality

of pairs of continuously arranged stands, 10 and a finishing mill comprising four single stands of rolls with interposed Y-transfer conveying mechanisms for the stock, the first and third of said Y-transfer conveying mechanisms being connected, for the delivery 15 of the stock, when desired, from the first to the fourth of said single stands of rolls.

Dated this thirtieth day of April, 1926.
JOHN W. SHEPERDSON.
